(57) **CLAIM**

I claim the ornamental design for a key tool, as shown and described.

DESCRIPTION

FIG. 1 is a perspective view showing a first embodiment of the key tool;

FIG. 2 is a left side elevational view thereof.

FIG. 3 is a right side elevational view thereof.

FIG. 4 is a top plan view thereof.

FIG. 5 is a bottom plan view thereof.

FIG. 6 is a front elevational view thereof.

FIG. 7 is a rear elevational view thereof.

FIG. 8 is a further left side elevational view of the first embodiment of the key tool with the key shown positioned for manipulating the key tool.

FIG. 9 is a perspective view showing a second embodiment of the key tool.

FIG. 10 is a left side elevational view thereof.

FIG. 11 is a right side elevational view thereof.

FIG. 12 is a top plan view thereof.

FIG. 13 is a bottom plan view thereof.

FIG. 14 is a front elevational view thereof.

FIG. 15 is a rear elevational view thereof.

FIG. 16 is a further left side elevational view of the second embodiment of the key tool with the key shown positioned for manipulating the key tool.

FIG. 17 is a perspective view showing a third embodiment of the key tool.

FIG. 18 is a left side elevational view thereof.

FIG. 19 is a right side elevational view thereof.

FIG. 20 is a top plan view thereof.

FIG. 21 is a bottom plan view thereof.

FIG. 22 is a front elevational view thereof.

FIG. 23 is a rear elevational view thereof.

FIG. 24 is a further left side elevational view of the third embodiment of the key tool with the key shown positioned for manipulating the key tool.

FIG. 25 is a perspective view showing a fourth embodiment of the key tool.

FIG. 26 is a left side elevational view thereof.

FIG. 27 is a right side elevational view thereof.

FIG. 28 is a top plan view thereof.

FIG. 29 is a bottom plan view thereof.

FIG. 30 is a front elevational view thereof.

FIG. 31 is a rear elevational view thereof.

FIG. 32 is a further left side elevational view of the fourth embodiment of the key tool with the key shown positioned for manipulating the key tool.

FIG. 33 is a perspective view showing a fifth embodiment of the key tool.

FIG. 34 is a left side elevational view thereof.

FIG. 35 is a right side elevational view thereof.

FIG. 36 is a top plan view thereof.

FIG. 37 is a bottom plan view thereof.

FIG. 38 is a front elevational view thereof.

FIG. 39 is a rear elevational view thereof.

FIG. 40 is a further left side elevational view of the fifth embodiment of the key tool with the key shown positioned for manipulating the key tool.

FIG. 41 is a perspective view showing a sixth embodiment of the key tool.

FIG. 42 is a left side elevational view thereof.

FIG. 43 is a right side elevational view thereof.

FIG. 44 is a top plan view thereof.

FIG. 45 is a bottom plan view thereof.

FIG. 46 is a front elevational view thereof.

FIG. 47 is a rear elevational view thereof; and,

FIG. 48 is a further left side elevational view of the sixth embodiment of the key tool with the key shown positioned for manipulating the key tool.

The writing shown on FIGS. 25-48 are two-dimensional indicia.

The broken line showing of environment is included for the purpose of illustrating portions of the key tool and form no part of the claimed design.
